UNITED STATES PATENT OFFICE.

FRANK NEARING, OF NEW YORK, N. Y.

ROTARY ENGINE.

1,241,755.

Specification of Letters Patent.

Patented Oct. 2, 1917.

Application filed July 12, 1916. Serial No. 108,878.

To all whom it may concern:

Be it known that I, FRANK NEARING, a citizen of the United States, residing at 62 West 93d street, borough of Manhattan, city 5 of New York, county of New York, and State of New York, have invented a new and useful Rotary Engine, of which the following is a specification.

My invention relates to improvements in 10 rotary engines to be operated by steam or any vapor, gas, explosive, or otherwise, or liquid, in which there are a number of segmental cylinders on a coupled shaft in two separate groups, each group set between independent adjustable bearings and each 15 group having equal piston areas on opposite sides of the shafts in each group and the cylinders of each group taking pressure simultaneously through a portion of the 20 revolution and each group taking pressure in turn before the cylinders of the preceding group have exhausted. The said cylinders are provided with intake and exhaust ports and radially moving abutments which are 25 operated by the action of two eccentric disks set on the main shaft, one disk is flattened for a portion of its perimeter and the other of correspondingly increased radius so that the distance from the center of a roller 30 against the side of one disk to the center of a similar roller against the opposite side of the other disk is always equal to the distance between the center of the said rollers measured across the circular portions 35 through the axis of rotation of the said disks. The said disks act against rollers mounted on cross-heads and the mechanism connecting the said cross-heads to the abutments causes the movement of the said abutments in the manner hereinafter described.

And the object of my improvements are, in a rotary engine:

First: A continuously applied pressure with the greatest effect.

Second: The elimination of the direct axial pressure from the drums and the pressure due to the reaction from the pistons—the consequent reduction of friction in all parts and lessening of vibrations through the 50 balancing of pressures.

Third: The prevention of piston leakage by the radially and longitudinally expansive pistons.

Fourth: The two part abutments and the 55 springs connected with them to prevent leakage and take up wear.

Fifth: The positive action of the abutments caused by the eccentric disks acting on the crossheads, connecting rocker arms, secondary rocker arms, cross connecting rods for reversed motion and the final rocker arms connecting to the abutment rod crossheads.

Sixth: The ability for group and individual adjustment of abutment throw through the movable adjusting sleeves on the rocker arms and the adjusting nuts on the abutment rods.

Seventh: The prevention of pressure leakage through the abutment entries by the 70 cylindrical stop valves.

Eighth: The access to the drums, pistons and drum keys, for their removal, repair, or replacement through the removable segments.

Ninth: The ability for automatic adjustment of the drums by the keys which are fixed in the drums and have some longitudinal movement in the keyways of the shafts.

Tenth: The ability to keep the shaft in 80 center by the independent adjustable bearings.

Eleventh: The ability to cut off one group and allowance for variation of alignment through the flanged and universal 85 couplings.

I attain these objects by the mechanism illustrated in the accompanying drawings; Figure (1) is a plan view of the whole machine showing the groups of cylinders. Fig. 90 (2) is a section taken on the lines 2—2, Fig. (3) is a section on the lines 3—3 of Fig. (1). Fig. (4) is a side view of the whole machine with guide standards cut away to show disks. Fig. (5) is a longitudinal section of one cylinder showing pistons cut away with keys, drums, and shafts in section. Fig. (6) is a section across one abutment showing bearings in cylinder heads and the two plates dovetailed together. Fig. 100 (7) is a view at center showing the eccentric disks and their connections. Fig. (8) is a sectional view of the adjustable main bearings. Fig. 9 is a view of C¹ or C³ cut away in portion to show the relative positions of the pistons and the abutments, the intake and exhaust ports, the drum keys, abutment stop valves, abutment rods, crossheads, guides, disk connections to rocker arms, reverse arms with connecting rods, removable segments, &c. Fig. 10 is a view of C⁴ or C⁶ similar to that shown in Fig. 9.

Fig. (11) is a sectional view of the abutment rod crossheads.

Similar letters refer to similar parts throughout the entire views. B is the base upon which all parts are mounted, C¹, C², C³, C⁴, C⁵ and C⁶ are the cylinders, C¹, C² and C³ form one group and C⁴, C⁵ and C⁶ form a second group.

C¹ and C³ have pistons on the same sides 10 of the shaft and C² has a piston on the opposite side of the said shaft, the area of the piston of C² being equal to the sum of the piston areas of C¹ and C³.

C⁴ and C⁶ have pistons on one side of the 15 shaft and C⁵ has a piston on the opposite of the said shaft the area of the piston of C⁵ being equal to the sum of the areas of the pistons of C⁴ and C⁶.

The shaft S¹ is mounted in the adjustable 20 bearings D¹, and carries the drums J, within the cylinders.

The said drums J are keyed to the shaft S¹ by the keys E², which are firmly fixed 25 between the jaws of the said drums J and are fitted to slide in the key ways of the shaft S¹ and the said key ways being somewhat longer than the keys.

The backs of the keys E² are inclined 30 outward from their centers to the cylinder heads and form seats or beds for the piston wings E¹, each of which is composed of two oppositely symmetrical parts which are halved and lapped for a portion of their length. The two said parts forming one 35 wing are each cut away for a short space at the center of each wing leaving openings in which springs T¹ are placed to hold the two parts of each wing against the cylinder heads and small openings or ports P² in the 40 piston jaws on the pressure side admit pressure to force the said wings against the heads and barrels of said cylinders by action in the spaces which are occupied by the said springs.

45 The shaft coupling K¹, is flanged to permit disconnection of one group and is packed somewhat apart with plates which may be increased or removed for adjustment.

50 The universal coupling K², permits some variation of alignment of the two groups.

The disks F¹ and F² are circular for somewhat more than 180 degrees the said circular portions being on opposite sides of the 55 shaft S¹. F¹ is flattened opposite its circular portion and F² correspondingly increased in its eccentric portion so that the distance from the center of a roller against the side of one disk to the center of a similar 60 roller against the opposite side of the other disk is always equal to the distance between the centers of the said rollers measured across the circular portions through the axis of rotation of the said disks.

65 The action of the circular portion of F¹

on the crossheads H¹, causes the closing of the abutments and the action of the eccentric portion of F² on the crossheads H¹, the opening of the said abutments to permit the passage of the pistons.

Bearing against opposite sides of the 70 disks F¹ and F² are the rollers N, mounted on the crossheads H¹, which slide on the guides L¹.

The said crossheads H¹ are connected by 75 the rods R¹, from the sides of one disk to the opposite sides of the other disk so as to keep the said rollers constantly against the said disks. The said rods R¹, are provided with springs T², between the heads of said 80 rods and their crosshead connections to ease the action of the said roller against the said disks.

The crossheads acting on the disk F², are connected by rods R², to sleeves clamped by 85 screws on the rocker arms G¹, so that said sleeves may be moved on the said rocker arms for group adjustment.

The rocker arms G¹, are fixed on the shafts S², which are mounted in bearings 90 along the abutment sides of C¹ and C³ and C⁴ and C⁶ and have fixed thereon the double rocker arms G⁴, for moving the abutments of cylinders C¹, C³, C⁴ and C⁶.

Upon the shafts S², are also fixed the 95 rocker arms G², which are coupled to the rods R³, extending across the engine and connected to the sleeves clamped with screws upon the rocker arms G³, said rocker arms G³ being fixed on the under sides of the 100 shafts S³, upon said shafts S³, are also fixed the double rocker arms G⁴, for moving the abutments of cylinders C² and C⁵ simultaneously with those of the other cylinders of their respective groups.

105 The connections of the rods R², and R³, to the sleeves on the rocker arms G¹, and G³, are formed by pins which extend through two parts of the said rods, the sleeves and slots in the rocker arms permitting movement of the said pins but the bearings of said pins being in the said sleeves.

The outer ends of the rocker arms G⁴, pass through the channeled circular disks U, which are seated in bearings for them in the 115 sides of the crossheads H², and the covers of said disks which are bolted to the crossheads H².

The crossheads, H², are pierced by the 120 abutment rods R⁴, and are mortised to fit nuts on the said rods R⁴, said mortise also makes space for springs T³, which press against the said nuts and the outer part of the mortise. The said nuts hold the said abutment rods during withdrawal and the 125 springs T³ cushion the thrust of the abutments as they strike the drums J.

The crossheads H², slide upon the guides L².

130 The abutment seats are a portion of the

movable segments V, and the abutment chambers A¹, are bolted on to an extension of the cylinders. The abutments are each in two parts one A², which inclose the T end 5 of the abutment rods and which slide in grooves in the cylinder heads. A³, are plates which bear on the plates A² and have a dove tailed lug through the plates A², against the said lugs are springs T⁴, which abut against 10 sections of the plates A² said springs forcing the parts A³ against the drums J when the abutments are closed.

The cylindrical metallic spindle packing A⁴, extends across the abutment plates A³ 15 and are placed loosely in chambers in the abutment extensions on the pressure sides and are provided with ports P³, which admit pressure and press the said packing A⁴ firmly against the said abutments to prevent 20 leakage in the abutment chambers.

The removable segments V, are between the exhaust ports X and the abutments.

The intake ports P¹, are located so as to admit pressure behind the pistons after the 25 abutments are closed.

In operation the pressure is admitted through the entry ports of the group in which the abutments are closed forcing the pistons of that group around through their 30 portion of the revolution and carrying the pistons and abutments of the other group around to the points where the last said group takes action and the exhaust of the preceding group is reached, the groups taking 35 action in rotation.

The group following in the group action, takes pressure before the group preceding it has exhausted insuring continuous pressure action without any dead point.

40 1. In a rotary engine having a plural number of segmental cylinders in separate groups and provided with intake and exhaust ports, the combination with the shaft carrying within said cylinders loosely keyed drums carrying radially and longitudinally expansive pistons on opposite sides of the shaft in each group, of the eccentric disks fixed on said shaft and the connecting mechanism for moving the abutments within said 45 cylinders substantially as shown and described.

2. A rotary engine comprising segmental cylinders in groups containing radially slid-

ing abutments and having mounted therein a horizontal shaft carrying pistons in combination with two eccentric disks fixed upon the said shaft, one of said disks being flattened for a portion of its perimeter, while the other has a corresponding portion of increased radius and connecting means whereby the rotation of the said disks causes the reciprocation of the said abutments substantially as shown and described. 55

3. In a rotary engine having a plural number of segmental cylinders in separate 60 groups connected by a common shaft upon which are fixed eccentric disks acting against rollers mounted on crossheads connected by rods to rocker arms fixed on secondary shafts having rocker arms fixed thereon which engage channeled disks working in crossheads connected by rods to abutments provided with packing and rocker arms connected by rods to rocker arms fixed on the undersides of shafts on the sides of the engine opposite 65 to the secondary shafts in each group, which third named shafts also carry rocker arms engaging channeled disks working in crossheads connected by rods to abutments provided with packing on the sides last named, 70 the combination with the eccentric disks working against rollers mounted on crossheads, of the connecting rods from said crossheads to sleeves clamped on rocker arms fixed on shafts on one side of each group and 75 said shafts also carrying rocker arms engaging channeled disks in the abutment rod crossheads of that side and also carrying other rocker arms which are connected by rods extending across the engine in each 80 group to sleeves clamped on rocker arms fixed on the under sides of shafts on the sides of the engine opposite to the aforesaid secondary shafts which third named shafts also have fixed thereon rocker arms engaging 85 channeled disks in the abutment rod crossheads on the sides last named and move the abutments of the sides last named in the opposite direction to that of the abutments first mentioned, substantially as shown and 90 described. 95
